Primary Examiner — Philip S Hyder*Assistant Examiner* — Keith Frank(74) Attorney, Agent, or Firm — Fross, Zelnick, Lehrman & Zissu P.C.; Charles T. J. Weigell, Esq.(57) CLAIM

The ornamental design for a package for garments, as shown and described.

DESCRIPTION

FIG. 1 is a front perspective view of a package for garments showing my new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dash-dash broken lines depict portions of the package for garments in which the design is embodied that form no part of the claimed design.

The dash dot dash broken lines depict environmental elements that form no part of the claimed design.
